CLAMP

Allan R. Duvall, San Francisco, Calif., assignor,
by mesne assignments, to Oliver United Filters
Incorporated, San Francisco, Calif., a corpora-
tion of Nevada

Application October 3, 1933, Serial No. 691,975

3 Claims. (Cl. 218—199)

This invention relates to a clamp for securing or anchoring the edges of a sheet of material, such as cloth, paper, woven wire or sheet metal. More particularly the invention relates to a clamp 5 for securing the filter medium of a filter to its support, base or frame.

For the purpose of filtering sugar cane settlings resort has been made to a punched sheet metal filtering screen or medium, but considerable difficulty has been experienced in securing this type of filter medium to the cylindrical surface of a continuous sectionalized rotary drum filter. As is well known in the filtration art, the drum of a continuous filter is divided into individual sections or compartments by spaced parallel division strips running longitudinally of the drum. To facilitate repair and inspection it is oftentimes desirable to cover each section or compartment with an individual panel of filter medium, rather than to cover the drum with a single continuous sheet of filter medium. Oliver United Filters Inc. with whom the applicant is associated has carried on considerable development work for the purpose of developing some means by which a perforated sheet metal filtering medium may be secured to the filter drum in the form of individual panels. One method which at first looked very promising was to form a dovetailed channel in each division strip. The edges of two adjacent panels of the sheet metal filtering medium were then inserted into this channel and secured in place by means of a lead caulking strip. The caulking was effected under sufficient pressure to force lead into the perforations of the filtering medium. However, actual field tests made by the applicant proved that within a period of two hours the filtering medium so secured had worked sufficiently loose to prohibit the further operation of the filter.

In general the object of this invention is the provision of a clamping mechanism by which the edge of a sheet of material can be securely but detachably anchored or locked in place.

More specifically the object of my invention is the provision of a base member having a channel therein formed with undercut walls, and within which a plurality of pairs of wedge shaped members is adapted to be accommodated for the purpose of detachably locking a sheet of material between the adjacent faces of the wedges and the channel.

The invention possesses other advantageous features, some of which with the foregoing will be set forth at length in the following descrip-

tion, where I shall outline in full that form of my invention which I have selected for illustration in the drawing accompanying and forming part of the present specification. In said drawing, I have shown one form of my invention, but it is to be understood that I do not limit myself to such form, since the invention as set forth in the claims may be embodied in a plurality of forms.

Referring to the drawing:

Figure 1 is a cross section of a portion of the periphery of a rotary drum filter illustrating one form of my invention as applied to the division strips of the filter.

Figure 2 is a plain view of that portion of the 15 rotary drum filter shown in Figure 1 with a part of the filtering medium broken away to show one of the filter compartments.

Figure 3 is a perspective view of one pair of 20 coacting wedge shaped members utilized in my invention.

Figure 4 is a perspective view of a curved clamp 25 adapted to be disposed peripherally of a filter drum when it is desired to divide the drum longitudinally into two individual filters.

As shown in Figure 1 a division strip 1 is secured to a cylindrical shell 2 in any suitable manner, such as by riveting. Secured either directly to the shell 2 or in the event that shallow compartments are desired, to a spacing member 3, 30 is a supporting screen 4 provided with ribs 5 which serve to hold the filter medium 6 in spaced relation with respect to the supporting screen 4, to thereby form the filter section or compartment 7. As is well known in the industry communication is established between each of the filter compartments and the filtrate valve by means of suitable filtrate pipes 8 secured to the filter drum by means of a fitting 9. The division strip 1 is provided with lateral flanges 11 which 40 overhang and rest on the edges of the supporting screen 4.

The division strip 1 is also provided with a channel 12 extending over its entire length, and it is to be particularly noted that the lateral walls 45 of this channel are undercut, and of uniform cross section throughout its length. As is shown in Figure 1 the cross section of the channel 12 is in the form of an isosceles trapezoid, but may be of any other form such as "half round" or 50 inverted T so long as undercut walls are provided. Accommodated within this channel and forming a clamp therewith is a plurality of pairs of coacting wedge shaped members 13 and 14. As shown in Figures 1 and 3 the outer side of the 55

wedges are not only undercut but are slightly fluted to snugly accommodate the upper edges of the channel 12. The wedges 13 and 14 are complementary so that when their inner faces 5 are in engagement their outer edges are always parallel regardless of the relative linear position of the wedges. It is also to be noted that the combined cross sectional area of the coacting wedges is uniform throughout their overlapping 10 sections regardless of their relative linear position.

To assemble the clamp above described the adjacent edges of any two adjacent panels of filtering medium 6 are disposed within the channel 12 and are made to conform as accurately as possible to its contour. From Figure 2 it will be noted that the mouth or narrowest part of the channel 12 is considerably larger than the maximum width of an individual wedge member, and that consequently the individual wedge members may be readily dropped into the channel. This construction is of importance for since the ends of the channel are closed by the ends or heads of the filter drum it would be impossible to insert the wedges endwise in the channels. Preferably a number of pairs of wedges are used. The first pair of wedge members should be moved to one extreme end of the channel, and then each subsequent pair made to abut the preceding pair. 25 It will be found that the last pair can be inserted into the remaining length of channel only if this remaining length is somewhat longer than the length of any single wedge member. The reason for this is of course that a wedging of 30 clamping action can be obtained only so long as it is possible to increase the combined cross sectional area of the coacting pair of wedge members by moving each member of the pair longitudinally relative to each other. The unoccupied portion of the channel remaining after the 35 last pair of wedge members has been inserted is then distributed throughout the entire length of the channel by moving each pair backward to a slight extent so as to leave each pair slightly spaced from its adjacent pairs. As a final step 40 the wedge members making up each coacting complementary pair are forced toward each other in a longitudinal direction to expand their combined cross sectional area and thereby securely 45 but detachably lock the filter medium 6 between wedge members and the walls and floor of the 50 channel 12.

To detach the filter medium the operation is reversed. The wedge members making up each 55 pair are forced away from each other to thereby decrease their combined cross sectional area. The spaces between each adjacent pair are then closed by making each pair abut the preceding pair to thereby leave sufficient free space by

which one of the wedge members can be removed from the channel.

To obviate any possibility of the loosening of the wedge members due to a difference in the coefficient expansion of the materials from which 5 the base member or division strip 11, the wedge members and the intervening filtering medium are made, it is desirable that all of these elements should be made either from the same kind of material or from materials which have substantially the same coefficient of expansion. 10

Actual field tests have shown that the type of clamp above described effectively holds the filter medium in place and furthermore permits the filter medium to be readily detached at will, 15 either for the purpose of replacing any given panel of filtering medium or inspecting any compartment without disturbing the remaining panels or compartments other than the two immediately adjacent panels and compartments. 20

Although my invention has been illustrated with particular reference to a rotary drum filter it is obviously applicable to any type of filter and may be used wherever it is of advantage to detachably secure or lock a sheet of material to a 25 base of supporting member. For example, in the construction of buildings this type of clamp may be conveniently used for securing the sheathing material to the interior or exterior building walls. By manufacturing the sheath- 30 ing in standard sizes and using a clamp of this nature it would be possible to save considerable time and labor in constructing buildings.

I claim:

1. A clamp for fastening a filtering medium 35 to the cylindrical surface of a rotary drum filter comprising: a division strip having a longitudinally extending channel therein formed with undercut walls and of substantially uniform cross section throughout its length; and a plurality of 40 pairs of complementary and co-acting wedge members accommodated within said channel.

2. In a rotary drum filter of the character described, a division strip; an undercut channel in said division strip adapted to accommodate one 45 end of a filter medium and a plurality of pairs of complementary and co-acting wedge members disposed within said channel for locking said filter medium therein.

3. In a rotary drum filter of the character described, a division strip; an undercut channel in said division strip both ends of which are closed and within which one end of a filter medium is adapted to be accommodated; and a plurality of 55 pairs of complementary and co-acting wedge members disposed within said channel for locking said filter medium therein.

ALLAN R. DUVALL.
